DISPENSING APPARATUS

Edmund F. Iannone, 12115 Clearglen Ave., and Woodward W. Holder, 421 N. Hill, both of Whittier, Calif.

Filed Aug. 26, 1963, Ser. No. 304,475

6 Claims. (Cl. 221—224)

This invention relates to a dispensing apparatus and more particularly to a dispenser for selectively dispensing relatively thin packets having irregular edges.

The use of individually wrapped products is greatly increasing in recent times. Of particularly widespread use are packets which are relatively flat with a square or other rectangular outline. Examples of products dispensed in such packets are: powdered foods such as soup, cloths for washing, and cloths for shining shoes.

These packets have the outstanding characteristic that they are very cheap to manufacture and are rugged. This results from the fact that such packets are essentially manufactured by placing the material to be packaged between two sheets of flexible material such as plastic and sealing the peripheral edges by means such as heat. The packets can be very rapidly made with the use of machines which automatically dispense into the packets the proper amount of material and seal them.

The packets will be used a great deal more if some means can be provided for selectively dispensing them. In such case, the packets can be sold on an individual basis without the necessity of an attendant—thus gaining the advantages of the coin operated dispensing machines which are in such wide spread use in the country.

We have found that there is a real need for a machine which can selectively dispense these flat flexible packets of materials such as a cloth saturated with a particular chemical. In the past, there have been suggested devices for dispensing such flexible packets. However, in those cases the flexible packets were joined together on opposite edges to form a long roll, which roll is placed in a machine which could dispense the packets one at a time. However, such rolls have the major disadvantage that the person servicing the dispenser is faced with the following dilemma. If he replaces the partially used roll he will waste the unused portion, or at least waste his time joining the unused portions to form a new roll. And, if he doesn't replace the partially used roll at the time of servicing, the dispenser may run out of supply before he returns to service the dispenser, thus causing a loss of income.

Accordingly, there is a need for a dispenser which can accommodate the flexible flat packets on a more individual basis such as dispensing them from a supply stack. In such case the service attendant does not have to throw away any packets, but merely has to place more packets on top of the supply stack.

In the past there has been suggested a dispenser for dispensing from a supply stack the flat flexible packets which the present invention accommodates. However, in that prior suggested device the packets had to be placed in special boxes in order to be useable in the machine. This is because the flexible packets have irregular edges and the devices have been unable to accommodate those irregularities in the packets. Although the cost of the extra boxes is not great, the cost is very significant as compared to the price of the packets. Further, the cost of putting the packets in the boxes is very undesirable.

Accordingly, it is an object of this invention to provide new and improved dispensing apparatus.

It is a further object of this invention to provide an improved dispenser which can accommodate packets of irregular shapes.

It is another object of this invention to provide a dis-

2

pensing apparatus which is economical to manufacture and operate.

It is still another object of this invention to provide a dispensing apparatus having means therein for selectively dispensing therefrom packets which have edges which are of irregular contour.

It is a still further object of this invention to provide an improved means for gripping along the edges flat objects having flexible edges of irregular contour.

Other and further objects of this invention will become apparent in the detailed description below in conjunction with the attached drawings wherein:

FIGURE 1 is a perspective view of the exterior of one embodiment of my invention;

FIGURE 2 is a frontal cross-sectional view of the dispensing apparatus taken along line 2—2 in FIGURE 1;

FIGURE 3 is a fragmentary plan view disclosing the packet selecting means with the transfer shoe in the front forward position;

FIGURE 4 is a fragmentary plan view disclosing the packet selecting means with the transfer shoe in the rear position;

FIGURE 5 is an exploded view of a major portion of the operating mechanism of the dispensing apparatus;

FIGURE 6 is a cross-sectional view of the dispensing apparatus taken along line 6—6 in FIGURE 2;

FIGURE 7 is a fragmentary cross-sectional view of the dispensing apparatus taken along 7—7 in FIGURE 2, but with some parts in another position;

FIGURE 8 is a partial cross-sectional view of the lower portion of the dispensing apparatus taken along line 8—8 in FIGURE 2;

FIGURE 9 is a partial cross-sectional view of the lower portion of the dispensing apparatus taken along line 9—9 in FIGURE 2; and,

FIGURE 10 is an enlarged fragmentary view of the coin clutch mechanism.

Referring now to FIGURES 1 and 2, the dispensing apparatus has a housing 11 with a front 12 which is removable in order that the attendant be able to gain access to the interior of the housing to replenish the supply of packets to be dispensed. The disclosed embodiment is to be used as a coin operated dispensing device. Accordingly, a money slot 13 opens through the front of cover 12 to receive the coin into the mechanism inside. After a proper coin has been dropped into slot 13, the person pulls handle 14 projecting through the cover 12 downwardly. And, as the handle 14 reaches the lower position a packet is dispensed through dispensing slot 15. In the event that the coin is of the wrong denomination, it is rejected by a mechanism inside of the housing and is returned to coin return slot 16.

Referring now to FIGURES 2 and 5 to 7, the particular embodiment of my invention will be described in further detail.

Located in the housing 11 is a supply holder means indicated generally by the arrow 20 for holding a supply stack of packets indicated by the arrow 21. The dispensing apparatuses which we have constructed are sized to accommodate packets approximately two inches by two and one-half inches and one-eighth thick at their centers. However, naturally, other sizes can be used without departing from the spirit of the present invention.

Located at the lower end of the stack of packets 21 are restraining means indicated generally by the arrows 24 for gripping several of the lower packets for the purpose of permitting a transfer means, indicated generally by the arrow 26, to move the lowest packet to a position projecting out of the front 12 of the housing 11. As will be explained in greater detail below, in this particular embodiment the restraining means 24 is operated by movement of the transfer means 26.

The motion of handle 14 is communicated to move the

transfer means 26 through a lever mechanism 28. The lever mechanism 28 generally comprises a drive lever 29 and an actuator lever 30 each of which are pivoted at their upper ends at bolt 31. As described below, the motion of the handle 14 is transmitted to actuator lever 30 and by means of a coin clutch means, indicated generally by arrow 32, the motion of the actuator lever 30 is only transferred to the drive lever 29 (and therefore, to the transfer means 26) when a proper coin has been deposited into the money slot 13.

Before going into the details of the construction of the dispensing apparatus certain portions of the manner in which the coins deposited into the apparatus will be described. Any coin deposited through slot 13 will fall through a tube 34 into a commercially available coin ejector mechanism 35 held to the side of the housing 11 by a series of studs 36. Since the coin ejector mechanism 35 is merely one of the many which can be conventionally purchased, we have not shown the details of that mechanism. If the coin is of proper size it will slide down the chute 37 to the coin clutch means 32 and take up the position of coin 38.

If the coin is of the wrong denomination, such that it is too small or too heavy, the coin ejector mechanism 35 will automatically cause the coin to by-pass the chute 37 and fall out through bottom 39 of the coin ejector mechanism into the coin return 16. The manner in which the coin ejector mechanism 35 is able to reject over-sized coins will be pointed out in further detail below.

Referring now to FIGURE 2, in more detail, the supply holder means 20 includes a left guide 41 and a right guide 42 which constrain the stack of packets 21 on the respective sides, while the housing 11 furnishing a support on the rear side of the stack. At the lower end of the guides 41 and 42 are provided horizontal inwardly extending supports 43 which will engage the portions of the lowest packet along the left and right edges of the packet. In FIGURE 2 the edges of the individual packets appear quite straight, i.e., planar, however, such is almost never the case. Spaced just above the supports 43 are front flanges 44 which function to assist the restraining means in restraining the packets above the lowest packet from moving forwardly with the lowest packet. It should be noted that the lower edge of the front flanges 44 are preferably spaced above the support 43 a distance equal to about one and one-half times the thickness of the packets.

As will be described shortly the lowest packet is moved to its position projecting from dispensing slot 15 by means of a transfer shoe which engages the underside of the lowest packet and moves it. Accordingly, we provide means for selecting the lowest packet to be dispensed.

In the preferred embodiment, the lowest packet is selected by the restraining means 24 slightly displacing the lowest packet in a direction away from the next above packet at a proper time in relation to the movement of the transfer shoe, while gripping the packets above. This diminishes the friction between the lowest packet and the next-above packet to a point substantially less than the frictional forces between the lowest packet and the transfer shoe—whereupon the lowest packet will move with the shoe to a position projecting from dispensing slot 15.

As mentioned above, a major difficulty is encountered in gripping the packets adjacent the particular packet to be dispensed. This is because the flexible edges of the packets are irregular. In FIGURE 6 the packets edges are shown to be quite regular in their shape. However, in practice, the packet edges are almost never the same contour because of handling in loading and other reasons.

In order to accommodate these irregularities along the edges of the packets, we provide sets of a large number of fingers which are inserted laterally into the side of the stack and thereby grip the packets near the bottom of the stack. Each of the fingers are individually rather flexible in order to accommodate the irregular edges. However, because of the large number of them their aggregate

strength is sufficient to grip the several lower packets in the stack to accomplish the intended function.

In the preferred embodiment, we have used a pair of front brushes 45 which are attached to axles 46 respectively, each of which axles have an offset crank portion 46a at the bottom thereof. The axles 46 are journaled at their upper end in upper journal member 47 having bearing holes 47a for that purpose (see FIGURE 5). Near the rear of the housing 11 there is provided a pair of brushes 48 which are attached to axles 49 having their respective upper ends journaled in the members 47 and having offset crank portions 49a at their lower end.

In the dispensing apparatuses which we have constructed, we have found that normal hog's hair bristle brushes will work quite satisfactorily. However, it should be understood that the restraining means could be made of such material as nylon and the fingers which are inserted between the packet can be made somewhat thicker. The fingers must have enough flexibility that they may accommodate the irregularities in the contours of the edges of the packets and will not grip the lowest packet so hard that the transfer shoe cannot move it.

Referring now to FIGURES 2 to 7, the transfer means 26 and the means of actuating the restraining means 24 will be described in detail. Disposed just below the left and right guides 41 and 42 is a generally U-shaped guide bracket 50 having a web portion 51 with a left flange 52 and a right flange 53 extending in these respective directions. The bracket 50 is secured to the rear wall of the housing 11 by suitable means passing through a mounting plate 54 provided at the rear edge of the bracket 50.

Disposed at the center of the web portion 51 is a guide slot 56 which cooperates with the transfer means 26 as will be described shortly. At the forward edge of the web portion 51 is a pair of depending portions 57 which are to receive one end of the spring for returning the mechanism for operating the restraining means 24.

It should also be noted that the left flange 52 is provided with a rear bearing slot 58 and a front bearing slot 59 extending laterally through the left edge of the flange. And, disposed in operative relation with the said slots 58 and 59 is a retainer spring 60 mounted by a screw 61 to the flange 52. This particular construction is used in order that the brushes 45 and 48 may be quickly positioned in the apparatus, facilitating manufacture and maintenance. In practice, the upper end of the particular axle, e.g., axle 46 is inserted into hole 47a. The spring 60 is moved outwardly in order to allow the axle 46 to be received into slot 59 where the spring will hold it when the spring is released.

The right flange 53 of the bracket 50 is similarly constructed. Rear bearing slot 63 and front bearing slot 64 are provided to receive the axles 49 and 46 respectively. Similarly a retainer spring 65, anchored to the flange 53 by a screw 66 releasably holds the axle 46 and 49 in operative position.

Disposed just below the bracket 50 and in slidable relation with the underside of the web portion 51, is located a cam-plate 68 having an actuation slot 69 disposed generally in the center thereof. The cam-plate 68 has a pair of left elongated openings 70 disposed near the left side of the plate. And, as will become evident, these slots 70 receive the crank portions 46a and 49a of the respective brushes 46 and 49 on the left side of the supply stack 21. Adjacent the right side of the cam-plate 68 is another pair of elongated openings 71. Similarly to elongated openings 70, the elongated openings 71 receive the offset crank portions 46a and 49a of the respective brushes on the right side of the stack.

Disposed at the rear of the cam-plate 68 is a pair of depending portions 72. As can be seen best in FIGURES 2, 6 and 7 a pair of return springs 74 are secured at their rear ends to the depending portion 72 and at their respective forward ends at the depending portions 57. By this

arrangement the cam-plate 58 is normally urged towards its forward position.

The office of cam-plate 68 is to swing the brushes 45 and 48 at the proper time. To this end, the respective crank portions 46a and 49a of the axles 46 and 49 are received into the elongated openings 70 and 71 as mentioned above. And, in order to support the cam-plate 68 from the bottom, each of the crank portions 46a and 49a have fastened thereon a collar 75.

With this arrangement, when the cam-plate 68 is moved toward the rear of the housing 11 the brushes 45 and 48 assume a position such as shown in FIGURE 4 out of the way of the stack of packets 21. Then when rearward force is taken away from the cam-plate 68 the springs 74 return the cam-plate forwardly swinging the brushes 45 and 48 ninety degrees into engagement with the stack of packets 21 such as illustrated in FIGURE 3.

As mentioned previously, the restraining means 24 is preferably operated by force received from the transfer means. Thereby the proper coordination of timing between the operation of the two means can be easily achieved. This coordination of timing will become apparent in the following description of the transfer means 26 and the manner in which it cooperates with cam-plate 68.

Disposed just above the web portion 51 of the bracket 50 is a transfer shoe 77 having a friction pad 78 thereon. A threaded hole 79 is located in the bottom of the shoe. Disposed just below the web portion 51 is located a slide bracket 80 having a depending arm 81 at its rear end. At its forward end the slide bracket 80 is provided with an upstanding guide portion 82 and a smaller upstanding index 83 at the upper edge of the guide portion. Through the center of the bracket 80 is a hole 84. Also provided is a shoulder bolt 85 which extends through the hole 84 and the slot 56 and is threaded into the hole 79 in the transfer shoe 77 whereby the shoe and the bracket 80 sandwich the web portion 51 between them in sliding relation. The index 83 is received into a hole (not shown) the bottom of the shoe 70 to prevent rotation of the shoe relative to the bracket 80. The guide portion 82 and the shoulder portion of the shoulder bolt 85 function to guide the assembly comprising shoe 77 and bracket 80 along the guide slot 56.

Before leaving the description of the transfer means 26 it seems appropriate to make a few comments about the friction pad 78. The friction pad 78 may be made of any one of a number of materials having a very high coefficient of friction. However, we have found that very good results are obtained by making the pad of natural latex. It should be understood that although we show a pad of friction material which is cemented to the shoe, the grip on the lower-most packet could be obtained in other ways. For example, the pad could be removably clipped to the shoe. Also the latex material could be coated directly on the shoe. Further, a less desirable, but useable approach would use vacuum to grip the lower-most packet.

As can be seen, by gripping the arm 81, the shoe 77 can be moved back and forth as desired. Further, it can be seen that as the shoe 77 is moved rearwardly the arm 81 will engage rear end 86 of the slot 69 and further movement of the shoe rearwardly will move the cam-plate 68 rearwardly. And, as mentioned above, rearward movement of the cam-plate 68 swings the various brushes 45 and 48.

Having described the restraining means 24 and the transfer means 26 in some detail, we will turn our attention to the lever mechanism 28 and the manner in which the motion of handle 14 is communicated to the transfer means.

In order to move the arm 81 rearwardly and accomplish the above desired results, the drive lever 29 is provided with an open eye 92 in upwardly extending lower end 93 of the said drive lever. Accordingly, as the drive lever 29 is swung about its pivot at 31 the shoe 77 is correspondingly moved. Slightly less than half-way up the drive

lever 29 there is located an offset portion 94 having a forwardly facing coin-slot 95 formed therein. And, just below the top of the drive lever 29 is located a spring tab 96 which receives the rear end of a drive spring 97 which in turn is secured at its forward end to an anchor tab 98 on the left guide 41.

Just below the upper end of the actuator lever 30 is located a spring tab 100 which receives therethrough the rear end of return spring 101 which is secured at its forward end to the above mentioned anchor tab 98. At its lower end 102, the actuator lever 30 has been bent complementarily to the offset portion 94 on the drive lever 29 and a rearwardly facing coin-slot 103 has been provided at a position in line with the coin-slot 95 on the lever 29. When the levers 29 and 30 are in forward position, as shown in FIGURE 6, the coin-slots 95 and 103 are in a position where they will receive a coin exiting the chute 37 which coin will function to transfer force from the actuator lever 30 to the drive lever 29. See FIGURE 10 in particular where the coin 38 is so functioning.

As can best be seen in FIGURE 5, the drive lever 29 is slightly offset near its upper end at 104. And it should also be noted that the actuator lever 30 is slightly offset at 105, a point which is substantially below the portion 104. This is done in order that the handle 14 may extend and operate in this just described area between the two levers 29 and 30.

The manner in which the handle 14 cooperates with the lever mechanism 28 will now be described. The handle 14 extends between the levers 29 and 30 and is swingably mounted at its rearward end on a pivot bolt 198. A return spring 109, secured around anchor pin 10 on the left guide 41 and through hole 111 in the handle 14, biases the handle 14 towards its upper position shown in FIGURE 6. Midway of the length of the handle 14 there is a depending tab 113 having a roller 114 mounted on a stub shaft 115. The roller 114 is on the right side of the tab 113 and is therefore shown in dash lines. As the handle is moved downward the roller 114 engages forward edge 116 (see FIGURE 5) of the actuator lever 30 moving the lever rearwardly. And if a coin, such as coin 38 is disposed in the coin-slots 95 and 102, the rearward motion of the arm 30 is transferred to the lever 29 and thence to the arm 81 to move the transfer shoe 77 and the restraining means 24. Extending above the handle 14 is a coin reject actuator arm 120 having a small flange 121 extending to the left therefrom. It should be noted that the arm 120 is bent out of the plane of the handle 14 and therefore, is located to the left of the drive lever 29. (See FIGURE 2.) Extending through the flange 121 is an adjustable screw 122. By the geometry of the handle 14 and the arm 120 in relation to the location of a lever 123 on the coin reject mechanism 35, each time the handle 14 is moved to its lower position (as seen in FIGURE 7) the screw 122 engages and depresses the lever 123 in the coin mechanism. This lever 123 has the function of ejecting any over sized coins which are stuck in the mechanism. Since any over sized coins deposited into the dispensing apparatus would not move down into the coin clutch mechanism 32, the handle 14 can be depressed to clear the coin reject mechanism 35 without the necessity of dispensing a packet. As mentioned previously, the coin reject mechanism 35 is conventional and the lever 123 is also conventional. Accordingly, the manner in which the lever 123 works in the interior of the coin mechanism 35 will not be described further.

Referring now to FIGURES 2, 5, 6 and 7 the preferred manner in which the coin is displaced from the coin clutch means 32 will be described. At the rear end of the left upper journal member 47 there is located a coin displacement slot 125. Just above the slot 125 is located a coin displacer 126 swingably journaled on a shaft 127 on a bracket 128 fastened to the rear wall of the housing 11. The coin displacer 126 is biased downwardly by a spring 75 129 to a position where heel 129a engages the rear of the

housing 11 and cam surface 130 is positioned to engage the coin 38.

As the arm 14 is depressed and the levers 29 and 30 move rearwardly, the coin 38 moves along the upper surface of the member 47. When the coin 38 moves to the position just forward of the slot 125 the cam surface 130 engages the upper edge of the coin 38. Further rearward movement of the coin 38 raises the coin displacer 126 against the spring 129. Further, rearward movement eliminates the support of the member 47 because of the slot 125 and the displacer 126 forces the coin 38 downward out of its position in the coin-slots 95 and 103.

When the coin 38 is forced out of the coin-slots 95 and 103 the handle 14 will remain depressed and the lever 30 will remain in the rearward position. However, the drive spring 97 will snap the drive lever 29 forwardly moving the shoe 77 forwardly and as the shoe moves forwardly the brushes will swing into engagement with the stack of packets. It should be noted in the illustrated apparatus that the brushes 45 and 48 are in the position of engagement throughout around 75% of the motion of the transfer shoe 77. That is, the brushes 45 and 48 will remain in the position shown in FIGURE 3 until the transfer shoe 77 is approximately three-quarters of the way to the rear. For illustration the shoe 77 is shown in phantom line 130a at the said position. At that point, the further motion of the shoe 77 will swing the brushes 45 and 48 out of the way. Conversely the brushes 45 and 48 begin to swing back into engaging position just as soon as the shoe 77 starts forwardly. Therefore the brushes are in engagement with the stack of packets 21 during the great bulk of the motion of the transfer shoe 77.

When the coin is displaced from the coin-slots 95 and 103 it falls downwardly into a coin bin 132. As best seen in FIGURE 2 a coin shield 131 is provided to eliminate the possibility that the coin might fall into the coin return 16.

As mentioned previously, the present invention has the ability of accommodating packets with irregular contours. However, the reliability of the present apparatus is diminished if the stack of packets gets too low, e.g., four or five. This is true even though normally a stabilizing weight 133 is used.

In order to effectively shut off the machine and return the coin deposited by prospective users, the following apparatus is provided. As can best be seen in FIGURE 2 there is located a supply indicator 134 pivotally mounted at 135 to the rear of the housing 11. The indicator 134 has a laterally projecting sensing finger 136 which extends over and engages the side of the stack of packets 21. The pivot 135 is considerably to the left of the center of gravity of the indicator 134. Therefore, the indicator leans the finger 136 against the stack of packets 21. Above the finger 136 is an upwardly extending arm 137 which terminates in a coin-diverting finger 138 which projects into the interior of the coin mechanism 35. By the conventional way that the coin reject mechanism 35 works, when the arm 137 moves to the right, the finger 138 intercepts the path of fall of the coins and diverts them past the chute 37 down through the bottom 39 of the coin mechanism into the coin return 16. And as can be seen, when the supply of packets 21 gets so low that the top of the stack is below the lower edge of the sensing finger 136, the supply indicator 137 will swing towards the right causing finger 138 to deflect the coins.

In operation the dispensing apparatus is operated as follows. A coin is deposited into coin slot 13 and falls through tube 34 into the coin reject mechanism 35. If the coin is an improper one it will be rejected as explained above. If the coin is a proper one it will be diverted into the chute 37 and fall into a position enclosed by coin-slots 95 and 103. With the coin in the coin-slots 95 and 103 downward movement of the handle

14 (which is transferred to the actuator lever 30 through the roller 114) will move the drive lever 29 rearwardly.

As will be pointed out in further detail below, during this rearward movement the friction pad 78 is not engaging the lowest packet of the supply.

As the arm 29 moves the shoe 77 approximately 75% of the way toward the rear, the depending arm 81 engages the rear end 86 of the slot 69 in the cam-plate 68 and begins to move the cam-plate rearwardly also. This action swings the brushes 45 and 48 from the engaging position shown in FIGURE 3 to the out-of-engaging position shown in FIGURE 4 when the shoe 77 is at its rearmost position. When the brushes 45 and 48 move out of engagement with the stack, the stack of packets 21 will drop slightly downwardly to come to rest on the supports 43.

Then, just as the shoe reaches its rearmost position, cooperation of the slot 125 and the coin displacer 126 displaces the coin from the coin slots 95 and 103 whereupon the shoe 77 commences to move forward.

During the first phases of the forward movement of the shoe 77, the brushes 45 and 48 swing into engagement with the stack and the bristles are forced in between the lower packets of the stack forcing them apart. This decreases the friction between the lowest packet and the packet next above. (It also decreases the friction between the other packets spaced apart, but we are not concerned about them since there is no lateral force applied to them.) This action also forces the lowermost packet 30 slightly harder down on the friction pad 78 on the transfer shoe thereby increasing the frictional forces between the lowest packet and the pad 78. As the shoe 77 continues to move forward it carries the lowest packet with it and moves the packet to a point where it projects from the dispensing slot 15 sufficiently that the purchaser can grasp the packet and pull it the rest of the way out of the machine.

At this point the lowest packet in the stack 21 is actually supported by the bristles of the brushes 45 and 48 rather than the support 43. (This can be seen in FIGURE 2.) This is preferred for the following reasons. If, when the purchaser removes the packet which he has purchased, the bristles are too weak to prevent the remainder of the stack 21 from forcing the then lowest packet down onto the supports 43, the said lowest packet will be engaged by the friction pad 78 the next time the shoe 77 is moved rearwardly. If this happens there is an increased possibility that the pad 78 will grip the packet sufficiently that it will crumple the packet rearwardly. This problem is particularly acute when dispensing very thin flexible packets.

While only a few embodiments of the present invention have been disclosed and described in detail, it will be apparent to those skilled in the art that such is by way of illustration only and numerous changes can be made to the particular embodiments shown without deviating from the spirit of the present invention.

Another example of such a change is to substitute for the preferred mechanism which swings the brushes 45 and 48 back and forth, a mechanism which would selectively rotate the brushes always in the same direction. This has the effect of intermittently moving the brushes into and out of engagement with the stack of packets, however, the mechanism is more complicated.

Accordingly, it is our intention that the present invention should be limited solely by the appended claims.

We claim:

1. Apparatus for dispensing individually a plurality of flat packets having irregular edges, said apparatus comprising:

means to hold said packets in a stack with their respective flat faces abutting;

means for selectively moving the lowest packet slightly in a direction away from the next above packet, said

means including a large number of thin, flexible fingers, which may be selectively inserted between said edges and packets; and transfer means for moving said lowest packet substantially from its position to which it was moved relative to the next above packet. 5

2. Apparatus for dispensing individually a plurality of flat packets having irregular edges, said apparatus comprising:

means to hold said packets in a stack with their respective flat faces abutting; 10

a large number of individual fingers operatively connected to said supply containing means for movement between a first position out of engagement with any of the packets in the supply containing means 15 and a second position projecting between the lowest packet in the stack and the packet next above, said fingers being grouped in sets, each set having a plurality of fingers, the fingers of each set being substantially contiguous, each of said fingers being flexible and weak so that they will deform sufficiently to receive an edge of the packet between adjacent fingers;

means for moving said fingers between said first and second position; 25

and means for moving said lowest packet substantially when said fingers are in said second position.

3. Apparatus for dispensing individually a plurality of flat packets having irregular edges, said apparatus comprising:

means to hold said packets in a stack with their respective flat faces abutting;

means for selectively gripping the packet next above the lowest packet, said means including a plurality of sets of fingers, each of said sets including a plurality of individually flexible and weak fingers which will accept therebetween an edge of the packet next above the lowest packet but which cooperate together to grip the packet next above the lowest packet; 35

and means for moving said lowest packet substantially from its position immediately below the gripped packet, said last mentioned means being operatively connected with the means for selectively gripping the next above packet so that the next above packet 45 is gripped as the transfer means moves the lowest packet substantially.

4. Apparatus for dispensing packets, said apparatus comprising:

a housing, said housing having an opening formed in 50 one side thereof;

means for holding a supply of packets within said housing;

a large number of individual fingers operatively connected with said supply holding means for movement between a first position out of engagement with any of the packets in the supply holding means and a second position projecting between the lowest packet and the packet next above, said fingers being grouped in sets, each set having a plurality of fingers, 55 the fingers of each set being in close relation, each of said fingers being flexible and weak so that they will deform sufficiently to receive an edge of a packet between adjacent fingers;

means for moving said fingers between said first and 65 second positions;

transfer means for transferring the selected packet to a position projecting at least part way out of said opening;

a handle projecting from the interior of the housing to 70 a position outside of the housing, said handle being movable between a first position and a second position, said handle being operatively connected with

said transfer means for causing the latter means to move the selected packet through the opening when the handle is moved from the first position to the second position.

5. Apparatus for dispensing packets, said apparatus comprising:

a housing, said housing having an opening formed in the front thereof;

means for holding a supply of packets in a stack within said housing;

a large number of individual fingers disposed on either side of the stack of packets, said fingers being grouped in sets, each set having a plurality of fingers, said fingers being operatively connected with said supply holding means for movement between a first position out of engagement with any of the packets in the supply holding means and a second position projecting between the packets at the bottom of the stack;

means for moving said fingers between said first and second position;

transfer means for transferring the selected packet to a position projecting to a position at least part way through said opening, said transfer means being operatively connected with said means for moving said bristles whereby movement of the transfer means operates the means for moving said fingers;

a handle projecting from the interior of the housing to a position outside of the housing, said handle being movable between a first position and a second position, said handle being operatively connected with said transfer means for causing the latter means to move the selected packet through the opening when the handle is moved from the first position to the second position.

6. Apparatus for dispensing generally flat pockets having irregular edges, said apparatus comprising:

supply means to hold said packets in a stack with the irregular edges exposed to either side of the stack; selecting means including a plurality of brushes having bristles, said brushes being mounted on either side of the stack for movement between a first position where the bristles are out of engagement with the packet in the supply means and a second position projecting between the packets at the lower part of the stack, said bristles having a sufficient strength to support the weight of the stack;

transfer means movable in first and then in a second direction for moving the lowest packet in the stack in the second direction substantially from its position, said transfer means being operatively connected with the selecting means so that the bristles are moved from the second position to the first position prior to movement of the transfer means in said second direction and then are moved back to the second position as the transfer means moves in the second direction, whereby the bristles hold the lowest packet out of engagement with the transfer means during the motion of the latter means in the first direction, permit the stack to drop into engagement with the transfer means, and then separate the lowest packet from the next above packet while the transfer means is moving in the second direction whereupon the lowest packet is moved with the transfer means.
